UNITED STATES PATENT OFFICE.

ADOLPH KEPPELER, OF BUTTE, MONTANA.

MIXING APPARATUS.

1,171,054.

Specification of Letters Patent. Patented Feb. 8, 1916.

Application filed March 23, 1914. Serial No. 826,581.

To all whom it may concern:

Be it known that I, ADOLPH KEPPELER, a citizen of the United States, residing at No. 323 South Montana street, Butte, in the 5 county of Silverbow and State of Montana, have invented certain new and useful Improvements in Mixing Apparatus, of which the following is a specification.

This invention relates to improvements in 10 liquid agitators, such as egg-beaters and drink-mixers, and its object is to provide an efficient agitator of simple construction which can be readily taken apart for cleaning.

15 This object is attained by the construction illustrated in the accompanying drawing, in which—

Figure 1 is a side elevation of the device; Fig. 2 is a vertical section thereof, and Fig. 20 3 is a horizontal section on the line 3—3 of Fig. 1.

25 The agitator comprises a rotary beater 4 connected to an electric motor 5, and a cage 6 inclosing the rotary beater.

The cage 6 is formed of wires 7 secured at their lower ends to the edge of a disk 8. The upper ends of the wires are secured to an outstanding flange 9 of a split ring 10 by passing the same through apertures in 30 the flange. The intermediate portions of the wires are bent out to give the cage a substantially pear-shaped contour. The bottom of the motor casing is provided with an internally threaded boss 11 into which is screwed the upper end of a tube 12 provided with an outstanding flange 13 at its lower end. The split ring 10 is clamped around the tube 12 just above the flange thereof by 35 means of screws 14 passing through outstanding ears 15 at the ends of the ring sections.

The disk 8 is made in two parts hinged together at 16, the hinge connection being off to one side of the center.

45 The beater 4 is formed of wires 17 con-

nected at their lower ends to a disk 18, the under side of which has a pivot 19 stepped in a bearing aperture 20 in the upper face of the disk 8. The wires 17 are bent to conform to the contour of the cage 6, and their upper ends are secured to a small disk 21 at the lower end of a stem 22. The intermediate portions of the wires 17 pass through apertures in a ring 23 whereby they are held in proper relation. The upper end of the 55 stem 22 is secured by a set screw 24 in a socket 25 in the lower end of the motor shaft 26.

In use, the agitator is immersed in a vessel containing the liquid or other material 60 to be acted upon and the motor is started, which will cause the beater 4 to rotate. The cage surrounding the beater prevents the liquid in which the agitator operates from rotating in a body, and at the same time acts 65 as a guard for preventing the beater from hitting against the walls of the vessel. By removing the screws 14, the cage may be readily swung open and removed from the beater.

70 I claim:

An agitator comprising a tubular support having an outstanding flange at its extremity; a ring clamped around said support behind the flange, an open cage carried by the ring and having a base portion formed of sections which are hinged together, a shaft passing through the tubular support, a beater carried by the shaft, said beater being located in the cage, and a bearing 75 on one of the aforesaid base sections of the cage, said bearing supporting the beater shaft.

80 In testimony whereof I affix my signature in presence of two witnesses.

ADOLPH KEPPELER.

Witnesses:

N. FRANK LEONARD,
CHARLES A. FISKE.
